UNITED STATES PATENT OFFICE.

ISAAC SNOW, OF LAWRENCE, MASSACHUSETTS.

SHUTTLE-EYE GUIDE PLATE.

Application filed December 17, 1924. Serial No. 756,467.

This invention relates to self threading shuttles and is an improvement on the type of shuttle shown in patents to Snow of June 29, 1920, No. 1,344,734, and of Feb. 22, 1921, No. 1,369,306, and patent to Allen, Oct. 28, 1913, No. 1,076,985.

In an automatic loom when the bobbin is shifted, at the first pick it is desirable that the yarn should automatically slip under a front hook and preferably also under a back hook or guide, and during the second pick should slip into the eye down in back of the horn and in front of the pin, and should stay there.

15 However at the beginning of the second pick there is a period when the yarn is slack and there is a tendency to kink. During this period there is a tendency for the yarn to drop or slip out from under the front hook, 20 and being kinked, to remain out during that part, and to run over the top of the shuttle block.

To prevent this, it is desirable that the front hook should extend down and forward.

25 This extending of the front hook forward however makes it more difficult for the yarn to pull back into position if it starts to run over the top and front of the shuttle block or guide plate.

30 The main feature of my device is the shaping of the front elevation of the front hook whereby the yarn will readily pull off and still allow the extension of the front hook.

In the drawings Fig. 1 is a plan view of a 35 shuttle with my improvement.

Fig. 2 is an elevation as from the bottom of Fig. 1, showing my shuttle block removed from the shuttle.

Fig. 3 is a sectional elevation as from the 40 right, on line 3—3, of Fig. 1, showing the shuttle block not in section, and the wood in section.

Fig. 4 is an elevation from the left of Fig. 2.

45 Fig. 5 is an elevation from the back of Fig. 2, or the left of Fig. 4.

Fig. 6 is a plan view similar to Fig. 1 showing a modification of my device.

50 S is a shuttle of the self-threading type for automatic looms, having the usual bobbin chamber 10 for the bobbin B from which the thread A is unwound in the direction of the arrow in Fig. 1. 12 is the thread chamber which extends forward in continuation of

bobbin chamber 10, and 13 is the delivery 55 passage which extends still further forward from the threading chamber.

H represents the shuttle eye in the wood, and this connects with the threading chamber 12 through the slot 15 cut away from 60 the delivery passage 13. 8 represents the metal tip of the shuttle.

This eye H is what is known as a left eye, as it is at the left when looking towards the tip 8 of the shuttle. 65

F represents a metallic threading block which is set into a recess in the wood of the shuttle and is shown as fixed therein by means of a screw 36 which passes through a hole in the wood of the shuttle and a hole 70 35 in the block, in a well known manner. Preferably there is also at the bottom of block F, the projection 34 which fits into a recess in the wood of the shuttle.

32 is the horn and 33 the thread pin, both 75 of well known form.

My improvement is more particularly useful in connection with a certain type of threading block such as shown in patents to Snow and Allen referred to herein and as 80 shown at F in Figs. 1 to 5, in which there is a thread directing guide plate G which extends from the top thereof and from the top side of the shuttle, down and out at 22 into the threading chamber 12, or that part 85 of the threading chamber which is enclosed in the threading block itself indicated at 9 in Fig. 1.

In Figs. 1 to 5, there is at or near the back a thread retaining guide hook or member 90 28 which is in extension of the sloping part 22 of guide plate G. As this together with the part 22 of guide plate G extends in the same direction and proximate the normal unwinding path of the thread as it unwinds 95 on the first pick of the shuttle in a magazine loom, that is in the direction of the arrow in Fig. 4, it is clear that it will slip into the part 9 of the threading chamber 12.

This is provided the axis of the bobbin B 100 somewhere nearly coincides with the center or axis of the passage 9 as should be the case and as shuttles are ordinarily constructed.

It is clear that when once in the passage 9, 105 the unwinding thread will travel around in the direction of the arrow as it unwinds from the bobbin, and there will be very little

likelihood of its unthreading even if there is no overlap locking device such as shown in certain other patents.

- The guide plate G which is shown as the top of shuttle block F extends from a point at about 17 substantially level with the top of the shuttle downward away from the eye H across a plane represented by X, Y, in Fig. 3, which extends vertically through the axis of the bobbin B when it is in position, and terminates at the front in a front hook 16 in extension of the top which curves down at 18 in a direction away from the shuttle eye, and thence downward towards the shuttle eye to the point 19. The front edge 3 extends in a substantially straight direction from about a point 117 which is about over the eye H forward, along and around hook 16 to the lower forward end thereof, 19.
- 20 The guide plate G at the back preferably also extends down into passage 9 in the form of a back hook 28 which extends sharply downward and thence at 24, over towards the side where the shuttle eye H is located.
- 25 Both hooks 16 and 28 extend down and around in the direction in which the yarn unwinds from the bobbin.

As shown in Fig. 5, I prefer that the distance from front to back of plate G along the line 90 to 91 in Fig. 5 should be greater than the distance 92, 93 so that any loop of yarn which may form will slip off.

I also prefer that the distance from front to back on back hook 28, along line 94 to 95 shall be greater than along the line 96 to 97, for the same reason, and that the front hook shall taper or grow gradually smaller from base to end from along the line 98, 99 to the tip. In the same way, the back hook from 40 96 to 97 to the tip should also grow smaller.

Any loops of yarn forming along 90, 91 or 94, 95 or 98, 99 will automatically slip off.

If a loop of yarn such as 5, shown in Fig. 1, forms while the shuttle is starting back on the second pick the front hook 16 extending forward in extension of the front edge of the guide plate G, and the fact that it curves downward in a direction away from the shuttle eye, and thence downward towards the shuttle eye, prevents the yarn from slipping down under the hook, and unthreading.

If the yarn escapes from the back hook 28 and starts up over the top of guide plate G as indicated at A in Figs. 2 and 3, the pull of the yarn around the point 30, back of the nose 32, is such that it will slip down from about the point 18 around the tip 19 of the nose, as this curve is such that, as it travels 60 it will always be getting closer to the point 30 from which the pull comes.

As shown in Figs. 2 and 3, if the yarn A slips up and over so that it runs over the top between 17 and 18, the pull from the 65 point 30 up in back of the tip 31 of nose 32

will cause it to slide down along 18, and around the bend to 19 from whence it will slip into place, and as the yarn unwinds it will be carried down around the end of back hook 24.

As shown in Fig. 6, the guide plate K may be fastened by means of pins 87 to the wood of the shuttle, and instead of a back hook may extend down in curve 83, the plate sloping down and over to the left at 84, and extending forward to the front hook 80 which is of the same shape as 18, and terminates at the point 82. The front edge 86 of guide plate K is not straight as is edge 3 of plate G, but curves in a well known manner.

As shown at 120 in Fig. 3, I prefer to extend a web down in behind hook 16 so as to keep the yarn pretty well down as it thereby helps to overcome any tendency of the yarn to run over the top, between 17 and 18, and cooperates with pull from point 30.

I claim:

1. The combination in a shuttle having an eye, a bobbin chamber, and a threading chamber in continuation thereof which connects with the eye, of a thread directing guide plate so fixed to the top side of the shuttle as to extend downward and across a plane extending vertically through the axis of a bobbin when in position in the shuttle and terminating in a nose which includes a front hook in extension of the guide plate which curves downward in a direction away from the shuttle eye and thence downward toward the shuttle eye, the front edge of the guide plate extending in a substantially straight direction diagonally from a point over the eye forward to the lower front end of the front hook, said guide plate extending sharply downward at its back part forming a back hook which at the bottom is bent over towards the side where the shuttle eye is located.

2. The combination in a shuttle having an eye, a bobbin chamber, and a threading chamber in continuation thereof which connects with the eye; of a shuttle block positioned in the threading chamber and having a thread directing guide plate at the top which extends from a position level with the top of the shuttle, downward and across a plane extending vertically through the axis of a bobbin, when in position in the shuttle, said block having a front hook in extension of its top which curves downward in a direction away from the shuttle eye, and thence downward towards the shuttle eye, said front hook tapering from its base to its end, the front edge of the shuttle block extending in a substantially straight direction, diagonally from a point over the eye thence forward to the lower front end of the front hook, the said shuttle block also having a back hook which extends sharply downward and thence over towards the side where the shuttle eye

is located, said back hook tapering from its base to its end, and its back edge and the front edge of the front hook coming closer together from the top of the guide plate to the ends thereof.

3. The combination in a shuttle having an eye, a bobbin chamber, and a threading chamber in continuation thereof which connects with the eye; of a shuttle block positioned in the threading chamber and having a thread directing guide plate at the top which extends from a position level with the top of the shuttle, downward and across a plane extending vertically through the axis 10 of a bobbin, when in position in the shuttle, said block having a front hook in extension of its top which curves downward in a direction away from the shuttle eye, and thence downward towards the shuttle eye, the front 15 edge of the shuttle block extending in a substantially straight direction diagonally from a point over the eye thence forward to the lower front end of the front hook, the said shuttle block also having a back hook which 20 extends sharply downward and thence over towards the side where the shuttle eye is located.

4. The combination in a shuttle having an eye, a bobbin chamber, and a threading chamber in continuation thereof which connects with the eye; of a shuttle block positioned in the threading chamber and having a thread directing guide plate at the top which extends from a position level with the 25 top of the shuttle, downward and across a plane extending vertically through the axis 30 of a bobbin, when in position in the shuttle, said block having a front hook in forward extension of its top which curves downward 35 in a direction away from the shuttle eye,

and thence downward towards the shuttle eye, the said shuttle block also having a back hook which extends sharply downward and thence over across the plane towards the side where the shuttle eye is located.

45

5. The combination in a shuttle having an eye, a bobbin chamber, and a threading chamber in continuation thereof which connects with the eye a delivery passage in forward extension thereof; of a shuttle block 50 positioned in the threading chamber and having a thread directing guide plate at the top which extends from a position level with the top of the shuttle, downward and across a plane extending vertically through the axis 55 of a bobbin, when in position in the shuttle, said block having a front hook in said delivery passage in forward extension of its top which curves downward and forward in a direction away from the shuttle eye, and 60 thence downward and forward towards the side where the shuttle eye is located, the said shuttle block also having a back hook.

6. The combination in a shuttle having an eye, a bobbin chamber, and a threading 65 chamber in continuation thereof which connects with the eye a delivery passage in forward extension thereof; of a shuttle block positioned in the threading chamber and having a thread directing guide plate at the 70 top which extends from a position level with the top of the shuttle, downward and across a plane extending vertically through the axis of a bobbin, when in position in the shuttle, said block having a front hook in said 75 delivery passage in forward extension of its top which curves downward in a direction away from the shuttle eye, and thence downward towards the shuttle eye.

ISAAC SNOW.
